CLAIM

The ornamental design for a rapid cardiac analysis tool for STEMI, as shown and described.

DESCRIPTION

FIG. 1 is a full open front view of a rapid cardiac STEMI identifying tool showing my new design;

FIG. 2 is an enlarged upper open front partial view thereof;
FIG. 3 is an enlarged lower open front partial view thereof;
FIG. 4 is a full open back view thereof;

FIG. 5 is an enlarged upper open back partial view thereof;
FIG. 6 is an enlarged lower open back partial view thereof;
FIG. 7 is an enlarged representational closed front view thereof;

FIG. 8 is an enlarged representational closed back view thereof;

FIG. 9 is an enlarged partial open lower side view thereof, the upper side view being similar in shape thereof; and,
FIG. 10 is an enlarged back view in condition of use, showing a time reference line and heart rate reference line thereof.

The broken lines are included for the purpose of illustrating portions of the rapid cardiac analysis tool for STEMI that form no part of the claimed design.

1 Claim, 10 Drawing Sheets
